[57] **CLAIM**

The ornamental design for a lockable slam latch, as shown and described.

DESCRIPTION

FIG. 1 is a front elevational view of a first embodiment of a lockable slam latch embodying my design;

FIG. 2 is a left side elevational view thereof;

FIG. 3 is a right side elevational view thereof;

FIG. 4 is a top plan view thereof;

FIG. 5 is a rear elevational view thereof;

FIG. 6 is a front elevational view of a second embodiment of the lockable slam latch embodying my design, the difference from the first embodiment residing in the addition of a mounting bracket;

FIG. 7 is a left side elevational view of the lockable slam

latch of FIG. 6;

FIG. 8 is a right side elevational view of the lockable slam latch of FIG. 6;

FIG. 9 is a top plan view of the lockable slam latch of FIG. 6; and,

FIG. 10 is a rear elevational view of the lockable slam latch of FIG. 6.

The broken lines showing a panel in which the lockable slam latch is mounted is for illustrative purposes only and forms no part of the claimed design.
